ENGINE STARTER

John W. Fitz Gerald, deceased, late of Milwaukee, Wis., by Mary C. Fitz Gerald, executrix, Milwaukee, Wis., assignor to Briggs & Stratton Corporation, Milwaukee, Wis., a corporation of Delaware

Application June 19, 1943, Serial No. 491,509

6 Claims.

(Cl. 74—7)

This invention relates to engine starters of the so-called automatic type wherein the operation of the starter automatically propels the pinion into and out of mesh with the ring gear of the engine.

In starters of this type it is essential that the drive transmission to the pinion include a yieldable or resilient element and this invention is concerned primarily with engine starters of the type wherein this necessary resiliency is afforded by a body of elastically deformable material such as rubber.

In all engine starters of this general class the anchorage of the pinion stop which defines the operative driving position of the pinion has presented difficulties, especially in the smaller starters where space is at a premium and the motor shaft is small in diameter.

It is therefore an object of this invention to provide a new and improved manner of anchoring the pinion stop with a view toward overcoming the difficulties heretofore encountered. To this end the invention broadly contemplates a yieldable anchorage for the pinion stop.

More specifically it is an object of this invention to provide a resilient or yieldable anchorage for the pinion stop so designed and constructed that the element which affords the resiliency in the driving connection between the pinion actuator and drive shaft also provides the yield for the pinion stop.

With the above and other objects in view, which will appear as the description proceeds, this invention resides in the novel construction, combination and arrangement of parts substantially as hereinafter described, and more particularly defined by the appended claims, it being understood that such changes in the precise embodiment of the herein disclosed invention may be made as come within the scope of the claims.

The accompanying drawing illustrates one complete example of the physical embodiment of the invention constructed according to the best mode so far devised for the practical application of the principles thereof, and in which:

Figure 1 is a view in side elevation with parts broken away and in section of a starter embodying this invention and showing the pinion in its retracted position; and

Figure 2 is a view similar to Figure 1 but showing the pinion advanced to its operative driving position.

Referring now more particularly to the accompanying drawing, in which like numerals indicate like parts, the numeral 5 designates a ring

gear of an engine to be started, with which a pinion 6 is adapted to be meshed. The pinion 6 is movable axially along and rotarily with a motor driven shaft 7 and is adapted to be automatically propelled into mesh upon initial rotation of the shaft 7 and to be withdrawn from mesh when the engine starts.

Such longitudinal propulsion of the pinion is effected by the relative rotation between it and 10 an actuator 8. The actuator 8 consists of a sleeve having external screw threads 9, and is mounted on a hollow shaft or tube 10 loose on the shaft 7.

The pinion 6 is carried by a tubular sleeve 11 which has an internally threaded nut member 12 fixed therein. The nut member is threaded on the actuator 8 and thereby supplies the screw threaded connection between the pinion and actuator by which relative rotation of these parts effects the desired advance and retraction of the 15 pinion. The nut member also cooperates with a flange 13 fixed to the tube 10 to support the pinion and its sleeve for longitudinal movement.

A resilient drive coupling indicated generally by the numeral 14 drivingly connects the actuator 20 with the motor driven shaft 7. This coupling consists of an annulus 15 of rubber or any other material having cubical elasticity confined between a driving abutment or flange 16 and a driven abutment or flange 17.

30 In the construction illustrated, the driving abutment 16 is fixed to the drive shaft 7 by a screw 18 and has a driving part 19 nonrotatably connected therewith, said driving part 19 being free to move axially with respect to the drive shaft 25 to apply axial pressure on the annulus 15 when the pinion reaches its operative driving position. The driven abutment 17 is part of or fixed to the actuator.

A shell 20 fixed to the abutment or flange 17 and engaging over the abutment or flange 16 limits the extent to which the abutments may 35 separate and also encloses the elastic annulus. The axial dimension of the shell 20 is such that it maintains the annulus under slight precompression to provide frictional driving engagement between it and the driving and driven abutments or flanges.

When the pinion reaches its operative driving 40 position its nut 12 collides with the flange 13 carried by the tube 10. The tube 10 thus has the impact of arresting the pinion advance transmitted thereto. A freely rotatable connection with the drive part 19 provided by a flange 21 on the 45 tube engaging behind the drive part restrains the 55

tube against axial movement in the direction of pinion advance.

As a result the movement of the pinion to its operative driving position is yieldingly arrested through the elastically deformable annulus 15.

The elastically deformable annulus thus not only serves as the resilient driving connection between the pinion actuator and drive shaft, but also provides yieldability for the pinion stop.

An anti-drift spring 22 confined between the stop flange 13 and the nut member 12 holds the pinion against creeping forward when the starter is idle.

From the foregoing description, taken in connection with the accompanying drawing, it will be readily apparent to those skilled in the art that this invention provides a starter of novel design and construction and that by virtue of the internal location and yieldability of its pinion stop it is particularly well adapted for small starters.

What is claimed as the invention is:

1. In an engine starter: a pinion movable to and from an operative driving position; a pinion actuator connected with the pinion and operable to actuate the pinion; a resilient drive for the pinion actuator including an elastically deformable member; a pinion stop at one side of and spaced from the elastically deformable member for limiting movement of the pinion to its operative position; and means extending from the pinion stop through and beyond said elastically deformable member to apply the pinion thrust on the stop to the elastically deformable member so that the pinion stop yields slightly as it arrests the advance of the pinion.

2. In an engine starter: a drive shaft; a pinion movable along the drive shaft to and from an operative driving position; a pinion actuator connected with the pinion and operable upon relative rotation therebetween to propel the pinion toward and from its operative driving position; means connecting the actuator with the drive shaft to hold the same against endwise movement in one direction while permitting free rotation of the actuator about the drive shaft; a resilient torque transmitting connection between the drive shaft and pinion actuator including a member axially yieldable; a pinion stop for limiting movement of the pinion as it reaches its operative driving position; and means for connecting the pinion stop to the drive shaft through said axially yieldable member and said connection between the pinion actuator and the drive shaft whereby pinion thrust against the stop is cushioned.

3. In an engine starter having a pinion and having a resilient torque transmitting connection through which torque is transmitted to the pinion and which includes an elastically deformable annulus frictionally engaged with driving and driven parts: a stop for limiting movement of the pinion when it reaches its operative driving position; and means connected at one end thereof to the stop and having its other end remote from the stop connected with the elastically

deformable annulus so as to restrain the stop against axial movement in the direction of pinion movement toward its operative driving position through said elastically deformable annulus whereby pinion thrust on said stop is translated into axial compression of said elastically deformable annulus.

4. In an engine starter: a drive shaft; a pinion movable along the shaft to and from an operative driving position; a pinion actuator operatively connected with the pinion and operative upon relative rotation therebetween to move the pinion longitudinally to and from its operative driving position; a resilient torque transmitting connection between the pinion actuator and the driving shaft comprising, a driven part on the actuator, a driving part nonrotatably and axially connected with the drive shaft, and an elastically deformable member between said driving and driven parts; means connecting the driven part with the drive shaft; means supporting the driven part from the drive shaft so as to maintain the elastically deformable member under a degree of precompression, said support leaving the pinion actuator free to revolve with respect to the drive shaft; a pinion stop for limiting movement of the pinion toward its operative driving position; and tension means connecting the pinion stop with the driving part so that the pinion stop is connected to the drive shaft through the elastically deformable member.

5. In an engine starter: a drive shaft; a pinion movable along the drive shaft; a barrel connected with the pinion; a nut in the barrel; a hollow screw-threaded pinion actuator threaded in said nut; a tube loose on the drive shaft and inside of and passing through the hollow screw-threaded pinion actuator; a stop fixed on the tube inside the barrel to be engaged by the nut when the pinion reaches its operative driving position; and a resilient torque transmitting coupling for driving the pinion actuator from the drive shaft having a connection with said tube by which the thrust of the pinion nut on the stop is cushioned.

6. In an engine starter: a drive shaft; a pinion movable along the drive shaft; a barrel connected with the pinion; a nut in the barrel; a hollow screw-threaded pinion actuator threaded in said nut; a tube loose on the drive shaft and inside of and passing through the hollow screw-threaded pinion actuator; a stop fixed to the tube inside the barrel to be engaged by the nut when the pinion reaches its operative driving position; a resilient driving connection between the pinion actuator and the drive shaft comprising, driving and driven parts engaging opposite sides of an elastically deformable member, the driving part being free to move axially with respect to the drive shaft; and a freely rotatable connection between the tube and said drive part whereby the tube and pinion stop receives support through the elastically deformable member.
